IGNITION SYSTEM FOR INTERNAL-
COMBUSTION ENGINES

Marion Mallory, Detroit, Mich.

Application October 30, 1943, Serial No. 508,300

7 Claims. (Cl. 123—117)

This invention relates to an ignition system for an internal combustion engine and more particularly to an ignition system which is controlled by the intake manifold vacuum.

An ignition system controlled by the manifold pressure is shown in my prior Patent 2,268,490. This invention is an improvement upon the ignition system shown in my prior patent.

It is the object of this invention to produce a manifold pressure timed ignition system in which the spark will be advanced when the car is decelerating with the clutch engaged and the throttle closed.

It is also an object of this invention to produce a manifold pressure timed ignition system in which the vacuum utilized in advancing or retarding the spark is more precisely controlled or varied in accordance with the timing best suited for the engine in view of the conditions under which it is operating.

Fig. 1 is a view partly in section showing my pressure timed ignition system.

Fig. 2 is a section along the line 2—2 of Fig. 1.

Fig. 3 is a section along the line 3—3 of Fig. 1.

The carburetor 1, adapted for attachment to an internal combustion engine, is provided with an intake passageway 8 having an air inlet end designated 9 and a fuel mixture outlet 10 through which the fuel mixture is adapted to pass into the engine intake manifold.

The passageway 8 includes the venturi 11 and, for purposes of description rather than by way of limitation, a booster venturi 12 is positioned within the main venturi 11. 13 designates the usual butterfly throttle valve mounted within the passageway 8 on shaft 3 which is swung open and closed by the rod 14 and crank 15. The fuel float bowl is designated 16. Fuel is drawn from the float bowl through passageway 17 into the mixing chamber.

A conventional timing mechanism is shown consisting of the usual rotatable cam 18 which operates the electrical circuit breaker 19 mounted on plate 20 which can be rotated clockwise to advance the spark and counterclockwise to retard the spark. A suction device 21 is used for advancing and retarding the spark. The suction device comprises a flexible diaphragm 22 backed up by a compression coil spring 23. The diaphragm is mounted in housing 24 which is connected to the carburetor by conduit 25. The diaphragm is connected to plate 20 by rod 26, one end of which is pivotally connected as at 27 to the plate 20 and the other end of which is fixed to the diaphragm. The wall 28 of the

housing is perforated so that the diaphragm is subjected on the outside to atmospheric pressure whereas on the inside of housing 24 the diaphragm is subjected through line 25 and passageway 29, orifices 30, 31, passageway 32 and orifice 33 to certain pressure conditions obtaining in and created by the intake passageway 8, as described below.

Passageway 29, between orifice 31 and the point at which passageway 32 communicates with passageway 29, is provided with a ball check valve 34 held against its seat by a compression spring 35. Compression spring 35 is strong enough to hold ball check 34 against its seat unless the car is decelerating with the throttle closed and the clutch engaged so that the car is driving the engine. Under such conditions the vacuum in the manifold on the engine side of throttle 13 will go higher than the manifold vacuum at idle and this vacuum will hold the check valve 34 away from its seat, thereby connecting orifice 31 with conduits 29 and 25 to advance the spark. This is important because the spark should be advanced when the car is overrunning the engine with the clutch engaged and the throttle closed, which produces a very high vacuum in the manifold.

Orifice 33 is positioned so that it falls on the outlet or engine side of throttle valve 13 as soon as the throttle valve is partially opened from idle position.

Passageway 29, between orifice 30 and conduit 25, is provided with a variable air bleed in the form of a piston valve 40 mounted in bore 41 and urged upwardly away from its seat 42 by compression spring 43. Valve 40 is provided with an opening or passageway 44 extending completely through the same. Valve 40 is held in the bore 41 by a screw plug 45 having a projection 46 which acts as a stop to prevent valve 40 from closing off passageway 29 above the valve 40. Valve 40 is provided with a flat face 47 to provide an air passageway between the valve and the face of bore 41. Valve 40 is controlled by the vacuum obtaining in passageways 32, 29 and 25 and plays the role of a variable air bleed to the suction device from the Venturi orifice 30.

If the engine is operating with the throttle only partly open to bring orifice 33 into the manifold vacuum, the vacuum is very high and the spark is advanced very high. At such time the vacuum will hold valve 40 down against its seat 42 so that orifice 30 is connected with conduit 25 only through passageway 44 in valve 40. This

restricts the amount that the suction device can be air bled through orifice 30. If the throttle is opened to about half way or more, the vacuum will drop in passageways 25 and 29 on the manifold or engine side of valve 40, thus permitting spring 43 to raise piston valve 40 off its seat 42 to bleed additional air into the suction device through orifice 30 and by the flat side 47 of valve 40 in addition to the air that bleeds through passageway 44 in the valve 40. Thus, it is evident from the above that valve 40 acts as a variable air bleed to the suction device.

I claim:

1. An ignition system for an internal combustion engine comprising an ignition timer, an intake passageway, a throttle valve in said intake passageway, a suction controlled device connected to said timer for advancing and retarding the spark, an orifice in the intake passageway positioned at all times on the atmosphere side of the throttle valve, a passageway connecting said orifice with the suction controlled device, a second orifice communicating with the engine side of the intake passageway when the throttle valve is in partly opened position, a second passageway connecting said second mentioned orifice with said suction device, and variable air bleed means positioned in the first mentioned passageway responding to vacuum conditions in the intake passageway for varying the communication between the first mentioned orifice and the suction device.

2. An ignition system for an internal combustion engine comprising an ignition timer, an intake passageway, a throttle valve in said intake passageway, a suction controlled device connected to said timer for advancing and retarding the spark, an orifice in the intake passageway positioned at all times on the atmosphere side of the throttle valve, a conduit connecting the suction device with said orifice, a second conduit for applying suction to the suction device from the engine side of the throttle valve in partly opened position whereby the first orifice acts as an air bleed when the throttle valve is in partly opened position, and variable air bleed mechanism between the orifice and the suction device responding to a high vacuum in the intake passageway on the engine side of the throttle valve to decrease the air bleed of the suction device through the first mentioned orifice and responding to a decrease in the manifold vacuum such as occurs when the throttle is open to increase the air bleed of the suction device through the first mentioned orifice and thereby retard the spark.

3. The combination as set forth in claim 2 wherein the variable air bleed mechanism comprises a vacuum operated valve having a fixed passageway therethrough which at all times permits communication between the first mentioned orifice and the suction device, and a second passageway which permits communication between said orifice and the suction device only when the valve is open.

4. An ignition system for an internal combustion engine for a vehicle comprising an ignition timer, an intake passageway, a throttle valve in said intake passageway, a suction controlled device connected to said timer, an orifice in the intake passageway on the engine side of said throttle valve, a second orifice in said intake passageway on the atmosphere side of said throttle valve, a conduit connecting said suction device with said orifices in the intake passageway, a check valve in said conduit normally shutting off

the suction device from the first mentioned orifice on the engine side of the throttle valve, said check valve opening only in response to a high vacuum at said first orifice such as occurs when the throttle is closed and the engine is overrun by the vehicle whereby spark is advanced.

5. An ignition system for an internal combustion engine for a vehicle comprising an ignition timer, an intake passageway, a throttle valve in said passageway, a suction controlled device connected to said timer for advancing and retarding the same, an orifice in the intake passageway on the engine side of said throttle valve, a second orifice in said intake passageway on the atmosphere side of said throttle valve at idle position and on the engine side of said throttle valve when the same is partly open, and a third orifice in the intake passageway at all times on the atmosphere side of said throttle valve, a conduit connecting said suction device with said orifices, and a check valve in said conduit normally shutting off the suction device from the first mentioned orifice on the engine side of the throttle valve and opening in response to a high manifold vacuum at said first mentioned orifice such as occurs when the throttle is closed and the engine is overrun by the vehicle whereby the spark is advanced.

6. An ignition system for an internal combustion engine comprising an ignition timer, an intake passageway, a throttle valve in said intake passageway, a suction controlled device connected to said timer for advancing and retarding the spark, an orifice in the intake passageway positioned at all times on the atmosphere side of the throttle valve, a passageway connecting said orifice with the suction controlled device, a second orifice in the intake passageway communicating with the engine side of the intake passageway when the throttle valve is in partly opened position, said second orifice communicating with the atmosphere side of the intake passageway when the throttle valve is in idle position, a second passageway connecting said second mentioned orifice with said suction device, and variable air bleed means positioned in the first mentioned passageway responding to vacuum conditions in the intake passageway for varying the communication between the first mentioned orifice and the suction device.

7. An ignition system for an internal combustion engine comprising an ignition timer, an intake passageway, a throttle valve in said intake passageway, a suction controlled device connected to said timer for advancing and retarding the spark, an orifice in the intake passageway positioned at all times on the atmosphere side of the throttle valve, a passageway continuously connecting said orifice with the suction controlled device, a second orifice in the intake passageway communicating with the engine side of the intake passageway when the throttle valve is in partly opened position, said second orifice communicating with the atmosphere side of the intake passageway when the throttle valve is in idle position, a second passageway connecting said second mentioned orifice with said suction device, and variable restricting means positioned in the first mentioned passageway responding to vacuum conditions in the intake passageway for varying the communication between the first mentioned orifice and the suction device.
